UNITED STATES PATENT OFFICE.

HENRY W. CORNING, OF CLEVELAND, OHIO, ASSIGNOR TO THE STANDARD SEWING MACHINE COMPANY, OF CLEVELAND, OHIO, A CORPORATION OF OHIO.

BOBBIN-WINDER FOR SEWING-MACHINES.

1,176,434.

Specification of Letters Patent. Patented Mar. 21, 1916.

Application filed October 1, 1915. Serial No. 53,531.

To all whom it may concern:

Be it known that I, HENRY W. CORNING, a citizen of the United States, and resident of Cleveland, in the county of Cuyahoga and State of Ohio, have invented certain new and useful Improvements in Bobbin-Winders for Sewing-Machines, of which the following is a specification.

My invention relates to that class of sewing machine bobbin-winders which are supported upon the vertical arm of the machine adjacent the machine drive belt and which comprise a rotatable bobbin-carrying spindle, a pivoted carrier for said spindle adapted for movement to and from an operative position with the spindle in driving engagement with the machine belt, and a lever operated by the accumulating thread on the bobbin having means for holding the spindle carrier in operative position during the winding of the bobbin and automatically releasing the same from such position when a predetermined amount of thread has accumulated on the bobbin.

The object of my invention is to simplify and render more efficient bobbin-winders of this class, which object I attain by means of the novel construction and combination of parts hereinafter set forth in detail and more particularly pointed out in the appended claims.

Referring now to the accompanying drawings forming part of this specification, Figure 1 is a front elevation of the rear end of a sewing machine provided with a bobbin-winder embodying my invention. Fig. 2 is a section taken on the line 2—2 of Fig. 1, looking in the direction indicated by the arrows. Figs. 3 and 4 are enlarged views of the bobbin-winder detached from the machine and showing the same in operative and inoperative positions, respectively, relative to the drive belt. Fig. 5 is a detail showing the connection between certain of the parts at that side thereof opposite the side shown in Figs. 3 and 4.

Similar reference characters indicate like parts in the several views of the drawings.

The part of a sewing machine here shown in connection with my improved bobbin-winder, comprises the arm 2, the drive pulley 3, and the drive belt 4. The bobbin-winder is adapted for detachable connection with the arm 2 and comprises a bracket arm 5 for the support of the other parts of

the device, which arm is attached to the machine arm 2 by means of a suitable fastening device, such as the screw 6. Adjacent the outer end of this bracket arm is pivoted, at 7, a frame 8 having at its upper end a 60 horizontally arranged bearing 9 in which is journaled a spindle 10, which latter is provided at one end with an attached pulley 11 for engagement with the drive belt 4 and at its other end is adapted to carry a removable 65 bobbin, such as 12.

The pivoted frame 8, which constitutes a carrier for the rotatable bobbin spindle 10, is maintained in its normal operative position by means of a lever 13 pivoted to the 70 bracket arm at 14 and having an arm 15 engaging a projection 16 on one side of the frame 8, as shown. This lever 13 is also provided with a second arm 13' adapted for engagement with the accumulating thread on 75 the bobbin whereby the lever will be moved or operated thereby.

As a means to hold the frame 8 in an operative position with the spindle 10, through its pulley 11, in driving engagement with 80 the belt 3, the arm 15 of the lever 13 is provided with a cam surface 17 which engages the projection 16 on the spindle carrier and holds the parts in their said operative position, as shown in Figs. 2 and 3. The formation of this cam 17 is such as to maintain holding engagement with the projection 16 during the upward swinging movement of the lever as caused by the accumulating thread on the bobbin and until the desired predetermined amount of thread has been accumulated, at which time the cam 17 will have been moved to a position to disengage from the projection 16 and thereby automatically release the spindle carrier 90 from its operative position with the spindle pulley in driving engagement with the drive belt. When the spindle carrier is so released, it will be held in its inoperative position as shown in Fig. 4 by the engagement of the 100 projection 16 with a stop surface 18 on the lever 13, as shown.

As a means to hold the lever 13 and the spindle carrier 8 in coöperative relation and cause the spindle carrier to swing backward to its inoperative position upon being released by the lever, I mount a coiled spring 19 upon the pivot 14 with one end engaging an arm 20 of the lever 13 to move the latter in a direction toward the spindle, and with 110

the other end engaging an ear 21 on the spindle carrier to move the latter in a direction backward from the drive belt, as in Fig. 4.

5 What I claim is:—

1. In combination with a sewing machine and driver, a bobbin-winder comprising a support, a rotatable bobbin-spindle, a carrier for said spindle movable to and from 10 an operative position with the spindle in driving relation with the driver, a lever operated by the accumulating thread on the bobbin having a cam loosely engaging the spindle carrier to hold the same in its said operative position during the winding of the bobbin and to automatically release the same 15 from such position upon the accumulation of a predetermined amount of thread on the bobbin, and a single spring engaging 20 both the spindle carrier and the lever and maintaining the same in coöperative relation.

2. In combination with a sewing machine and driver, a bobbin-winder comprising a

support, a rotatable bobbin-spindle, a carrier 25 for said spindle movable to and from an operative position with the spindle in driving relation with the driver, a lever operated by the accumulating thread on the bobbin having cam and stop surfaces, the cam 30 surface holding the spindle carrier in its said operative position during the winding of the bobbin and automatically releasing the same from such position upon the accumulation of a predetermined amount of 35 thread on the bobbin, and the stop surface engaging the spindle carrier following its release by the cam and holding the same in its inoperative position, and a single spring engaging both the spindle carrier and the 40 lever and maintaining the same in coöperative relation.

Signed at Cleveland, in the county of Cuyahoga, and State of Ohio.

HENRY W. CORNING.
